DRY SHAVER

Rasmus M. Hvid, Wilmette, Ill., assignor to Veed
Corp., Chicago, Ill., a corporation of Illinois

Application August 22, 1947, Serial No. 770,122

9 Claims. (Cl. 30—43)

1

This invention relates to dry shavers or shaving devices, more particularly to dry shavers of the type in which the shaving operation is carried out by a shearing action without recourse to driving motors or similar sources of power, and the invention has for an object the provision of improved devices of this character.

Heretofore dry shavers or razors of the hand-operated or powerless type have been provided with a thin cylindrical shield or guard having perforations or openings therethrough for receiving the hairs as the shield or guard is rolled across the skin, and cutters or blades disposed within the shield have been arranged for co-operation therewith to provide a shearing action. Such prior devices have not been entirely satisfactory, however, due to improper design and correlation of the shields and cutters, resulting in hair pulling and faulty cutting action; due to the difficulties involved in assembling and disassembling the devices for cleaning and replacement purposes; and due to high maintenance costs. Accordingly it is a further object of this invention to provide an improved dry shaver or shaving device of this type which is capable of effecting a satisfactory shaving operation even in the hands of an unskilled user, which is composed of a minimum number of readily removable parts that may be quickly and easily assembled and disassembled, which may be economically manufactured, and which will have a long useful life without the necessity of maintenance or repair.

In carrying out the invention in one form, a shaver is provided having a central core member, a hollow perforated cylinder mounted for free rotation around the core member for rolling engagement with the skin, a cylindrical cutter rotatably mounted on the core member within the hollow cylinder and having a plurality of longitudinally extending cutting teeth on the periphery thereof, and a lost motion connection between the cutter and the core member for limiting the relative rotation therebetween so that the cutter may rotate with the hollow cylinder during a portion of each shaving stroke and will be held against rotation during the remainder of each stroke to provide a proper cutting action. Preferably the longitudinally extending teeth on the periphery of the cylindrical cutter are formed by providing spaced longitudinally extending grooves in the periphery of the cutter, the side walls of the grooves being undercut so as to intersect the peripheral surface of the cylinder at an angle less than 90 degrees, thereby provid-

2

ing sharp cutting edges of less than 90 degrees included angle.

The shaver is composed of three radially separable parts, one of which comprises a cutter assembly including the core member and the cylindrical cutter, the second of which comprises the hollow perforated cylinder, and the third of which comprises a handle assembly including a handle member adapted to be telescoped over an extending end of the core member and secured thereto in non-rotatable relation by means of an axial rotatable part of the handle member.

For a more complete understanding of the invention, reference should now be had to the drawing, in which:

Fig. 1 is an enlarged longitudinal sectional view of a shaving device embodying the present invention, certain parts thereof being shown in elevation;

20 Figs. 2, 3, 4, and 5 are transverse cross-sectional views, respectively taken along the lines 2—2, 3—3, 4—4, and 5—5 of Fig. 1;

Fig. 6 is an enlarged developed view of a portion of the perforated hollow cylinder illustrating the arrangement and interrelation of the perforations; and

Fig. 7 is an enlarged sectional view of a portion of the cutter member showing the manner in which the cutting teeth are formed thereon.

30 Referring now to the drawing, the invention is shown as embodied in a shaver 10 having a center core member or shaft 11 which forms the main supporting element for the remaining parts of the shaver. Adjacent the left-hand end of the core member, as viewed in Fig. 1, there is provided a somewhat enlarged splined portion 12 adapted to be pressed into a suitable aperture in an end cap 13 which is substantially hemispherical and provides a finished appearance at this end of the shaver. As shown, the end cap 13 is provided adjacent its inner surface with an annular groove 14, the transverse wall of which provides a thrust bearing surface for a hollow perforated cylinder 15 which forms the shield or guard and will be more fully described hereinafter.

Mounted on the core member 11 adjacent the end cap 13 is a cylindrical cutter member 16 having a plurality of longitudinally extending cutting teeth 17 formed in the periphery thereof, as will be more fully described hereinafter, the cutter 16 being supported at its opposite ends by bearings 18 and 19 which have a press fit with the inner circumference of the cutter 16, and which have a free-running fit with the center core member 11. The cutter 16 and its supporting

bearings 18 and 19 may be secured in proper position on the core member 11 by means of a spring washer 20 which engages a groove 21 formed in the core member 11 in proper spaced relation to the end cap 13 so that the washer 20 and the inner surface of the end cap 13 form thrust bearings for the cutter 16, suitable clearance being provided to permit end play of the cutter. As shown, the portion of the bearing 18 which extends outwardly beyond the cutter 16 is provided with a slot 22 adapted to receive a pin 23 which projects outwardly from the inner surface of the end cap 13 so as to provide a lost motion connection between the cutter 16 and the core 11, whereby rotation of the cutter 16 on the core member 11 is limited to an angle of rotation determined by the width of the slot 22.

Also mounted on the core member 11 is a handle 24 which is preferably formed of some suitable plastic molded material, the handle 24 being hollow throughout its length and being provided adjacent the left-hand end thereof with a suitable bushing 25 which is preferably provided with enlarged splined portions 26 adapted, when the bushing is forced into the hollow handle, to cut grooves in the plastic material whereby the bushing is rigidly fixed in the handle against ready removal therefrom in an axial direction. Adjacent its left-hand end, as viewed in Fig. 1, the handle 24 is provided with a head member 27, a suitable enlarged portion 28 of the bushing 25 being arranged to hold the head member 27 securely on the handle 24 when the bushing is assembled in the handle. As shown, the head member is provided with an annular groove 29 in one face thereof, which groove forms a suitable thrust bearing for the hollow perforated cylinder 15 after the handle has been assembled on the core member 11.

The core member 11, as shown in Fig. 1, extends into the handle 24 beyond the bushing 25, and the extending end portion thereof is flattened on opposite sides, the flattened portions being indicated by reference numeral 30, and the extreme end of the core member 11 is provided with suitable threads 31 for a purpose to be more fully explained hereinafter. As shown best in Fig. 5, the right-hand end of the bushing 25 is provided with a flat-sided aperture 32 so that telescopic assembly of the handle 24 on the core member 11 will, through engagement of the flat sides of the aperture 32 with the flattened surfaces 30 of the core member 11, retain the handle and core member in non-rotatable relation with respect to each other.

At its extreme right-hand end the handle 24 is provided with a suitable tip or cap 33 which is likewise preferably formed of a suitable molded plastic, and which, as will be hereinafter described, is secured to the handle 24 in axially fixed, rotatable relation thereto. As shown, the right-hand end of the handle 24 is provided with a suitably shaped notch or groove 34 for receiving the ring-shaped portion 35 of a suitable clip 36, which is arranged so that its free end resiliently engages the outer surface of the handle 24 whereby the shaver 10 may be carried in a pocket of the user in the same manner as conventional fountain pens or pencils. The clip 36 is permanently secured to the handle 24 by means of a ring 38 which is provided with a recess 39, as shown, to receive the head of a threaded lock member 40, the head portion of the member 40 having a suitable notch 41 therein for receiving a tool by means of which the lock member 40 may be threaded into and tightened in

the end of the handle 24. It will, of course, be apparent that the ring 38, the peripheral surface of which may be suitably engraved with the owner's name or initials, may be omitted if desired, and the lock member 40 arranged to engage directly the ring portion 35 of the clip 36, in which case the end member 33 will be suitably shaped to permit nesting of the head of the lock member 40 within the open end thereof.

10 In order to mount the cap 33 on the handle 24 in axially fixed rotatable relation, a lockpin 42 is provided having a center portion of a diameter such as to extend through and provide a running fit within the lock member 40. At its inner end the lockpin 42 is provided with an enlarged portion 43 so as to define a shoulder 44 adapted to engage the inner end of the lock member 40. This enlarged portion 43 of the lockpin 42 is tapped to provide threads 45 adapted to engage the threads 31 on the end of the core member 11. The lockpin 42, as shown, extends outwardly beyond the member 40, and is provided with a collar 46 having a splined portion 47 adapted to be forced into the axial aperture 48 in the cap 33 so as to secure the cap 33 on the collar 46. As shown, the collar 46 and the extending end of lockpin 42 are drilled to receive a transverse pin 49 which serves to secure the collar 46 on the lockpin in non-rotatable, fixed, axial relation.

30 In assembly of the cap 33 on the handle 24, the lock member 40, the lockpin 42, the clip 36 and the ring 38 are first assembled and the assembly is inserted into the open right-hand end 35 of the handle whereupon the lock member 40 is threaded into place and tightened in the handle 24. The collar 46 may then be positioned on the extending end of the lockpin 42, and the pin 49 inserted through the transverse apertures to lock the collar in place, whereupon the end cap 33 may be forced over the collar 46 in the position shown, thus completing the assembly operation.

40 It will now be apparent that the shaver 10 consists of three principal parts, the first of which 45 is a cutter assembly that includes the core member 11, the cutter 16 and its bearings, the end cap 13, the pin 23 and spring washer 21, all of which are permanently assembled together in the relation shown; the second of which constitutes the hollow perforated cylinder 15, and the third of which is a handle assembly that includes the handle 24, the bushing 25, the lockpin 42 which is rotatably supported in the lock member 40 that supports the clip 36 and the ring 38, 50 and the end cap 33 with the bushing 46 and the pin 49 carried by the lockpin.

55 In order to assemble the shaver, it is necessary only to slip the cylinder 15 over the core member and the cutter from the right-hand end, as 60 viewed in Fig. 1, and then to place the handle assembly on the extending end of the core member 11 so that the flattened portion of the core member extends through the aperture 32 in the bushing 25 and the threaded end of the core member 11 engages the threads 45 in the lockpin 42. Engagement of the flattened portion of the core member with the bushing 25 restrains the handle 24 and the core member against relative rotation, and when the cap member 33 is 65 thereupon rotated, the handle assembly and the cutter assembly will be drawn together until the enlarged collar 28 on the bushing 25 engages the washer 20 at the right-hand end of the cutter. When the cap member 33 has been rotated sufficiently to bring these parts into firm 70 75

engagement, the head member 27 will be so positioned that the groove 29 therein which forms a thrust bearing for the perforated cylinder 15, will be spaced from the corresponding thrust bearing in the end cap 13 a distance greater than the length of the cylinder 15 so as to provide a free-running fit and some end play. For proper cooperation of the perforated cylinder 15 and the cutter 16, the grooves 14 and 29 in the members 13 and 27, respectively, are of sufficient depth to provide peripheral surfaces of smaller diameter than the diameter of the cutter 16 so that the perforated cylinder 15 is supported for rotation solely on the cutter 16.

The perforated cylinder 15 may be formed of rustless steel approximately .0025 to .003 of an inch in wall thickness, and provided with a large number of small, closely spaced perforations 50 (Fig. 6) arranged in staggered rows, as shown.

As shown best in Fig. 7, the cutting teeth 17 on the cutter 16 are formed by providing on the periphery of the cutter a plurality of longitudinally extending spaced-apart grooves 51 the side walls 52 of which are undercut, as shown, so as to intersect the surfaces of the cylindrical cutter at an angle substantially less than 90 degrees. Thus, as indicated in Fig. 7, the plane of each side wall 52, as represented by the dot-and-dash line 53, extends at an angle of 15 degrees to a radially extending line identified in Fig. 7 by the reference numeral 54. Therefore, the angle "a," as identified in Fig. 7, is, at the periphery of the cutter 16, in the neighborhood of 75 degrees. Consequently sharp cutting edges are provided, and the engagement of the outer surfaces of the teeth 17 with the inner periphery of the perforated cylinder 15 during operation of the shaver provides a honing effect on the teeth 17 and self-sharpening action is thus obtained. The grooves 51 in the teeth 17 extend throughout the length of the cutter 16, and while any desired number of teeth may be provided, it has been found that a satisfactory cutter is obtained with 20 teeth evenly spaced about the periphery of the cutter. While the longitudinally extending teeth 17 have been shown as being rectilinear, it will be understood that the cutter may be provided with longitudinally extending teeth having a helical pitch of any desired angularity.

With the shaver 10 assembled as shown in Fig. 1, the shaving operation may be quickly and satisfactorily carried out merely by grasping the handle 38 in one hand and moving the shaver across the skin so that the perforated cylinder 15 engages the skin and has imparted thereto a rolling movement. The shaving operation is accomplished by a series of back-and-forth strokes of the shaver, and the lost motion connection between the cutter 16 and the core 11, provided by the slot 22 and the pin 23, is effective to prevent hair pulling or improper shearing at the initiation of each shaving stroke. Assuming that the pin 23 occupies a central position in the slot 22, as viewed in Fig. 2, and that the shaver is then moved across the skin in the direction indicated by the arrow 55, with the skin engaging the lower surface of the cylinder 15, the cylinder will be caused to rotate in a clockwise direction, as indicated by the arrow 56, and during initial movement in this direction the cutter 16 will move with the cylinder 15 until the pin 23 engages the left-hand wall of the slot 22. Upon engagement of the pin 23 with this wall of the slot 22, the cutter will

become fixed relative to the core member 11, and the subsequent relative rotation between the perforated cylinder 15 and the cutter 16 will serve to shear-off the hairs which project through the apertures 50 in the cylinder 15. When at the end of the desired stroke in the direction of the arrow 55 a reverse stroke is started, the cylinder 15 and the cutter 16 will rotate together in the opposite direction until the pin 23 has moved across the slot 22 so as to engage the right-hand wall thereof, whereupon the cutter 16 will again become fixed on the core member 11. Thus it will be seen that during the initial portion of each stroke, the cutter is free to rotate with the cylinder 15, and the shearing action does not commence until a sufficient velocity of movement has been attained to assure a proper shearing action.

When it is desired to clean the shaver after completion of the shaving operation, it is necessary only to rotate the end cap 33 relative to the handle 24 until the threaded end 31 of the core member and the threads 45 in the lockpin 42 become disengaged, whereupon the handle assembly and the perforated cylinder 15 may be readily slid off of the core member 11 and the cutter 16, respectively. Thus the interior of the cylinder 15 and the cutting teeth of the cutter 16 are made available for the removal of accumulative hair clippings, and re-assembly after cleaning may be accomplished merely by telescoping the cylinder 15 over the cutter 16 and by then telescoping the handle 24 over the extending end of the core member 11 until the cooperating threads 31 and 45 are brought into engagement, the assembly operation then being completed by proper rotation of the end cap 33.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. A shaver comprising a core member, a hollow perforated cylinder mounted for free rotation about said core member for rolling engagement with the skin as said shaver is moved through alternate oppositely directed shaving strokes, a cutter rotatably mounted on said core member within said hollow cylinder and having a plurality of longitudinally extending cutting edges spaced about the periphery thereof and adapted to engage the inner surface of said perforated cylinder, and means on said cutter and said core member providing a lost motion connection for limiting to a predetermined angle the relative rotation therebetween whereby said cutter is frictionally driven by and rotates with said hollow cylinder during an initial portion of each shaving stroke following a reversal of the direction of travel and is held against rotation during the remainder of each stroke.

2. A shaver comprising a core member, a hollow perforated cylinder mounted for free rotation about said core member for rolling engagement with the skin as said shaver is moved through alternate oppositely directed shaving strokes, a cylindrical cutter rotatably mounted on said core member within said hollow cylinder and having a plurality of longitudinally extending cutting teeth on the periphery thereof, said cutting teeth being defined by spaced longi-

tudinally extending grooves in said cutter the side walls of which are undercut to intersect the peripheral surface of the cutter at an angle less than 90°, and means on said cutter and said core member providing a lost motion connection for limiting to a predetermined angle the relative rotation therebetween whereby said cutter rotates with said hollow cylinder during an initial portion of each shaving stroke following a reversal of the direction of travel and is held against rotation during the remainder of each stroke.

3. A shaver comprising a core member, a hollow perforated cylinder mounted for free rotation about said core member for rolling engagement with the skin as said shaver is moved through alternate oppositely directed shaving strokes, a cutter rotatably mounted on said core member within said hollow cylinder and having a plurality of longitudinally extending cutting edges spaced about the periphery thereof and adapted to engage the inner surface of said perforated cylinder, a handle mounted on said core member in axial alignment with said cutter and said cylinder, and pin and slot means on said cutter and said core member for providing a lost motion connection for limiting to a predetermined angle the relative rotation therebetween whereby said cutter is frictionally driven by and rotates with said hollow cylinder during an initial portion of each shaving stroke following a reversal of the direction of travel and is held against rotation relative to said handle and core member during the remainder of each stroke.

4. A shaver comprising a core member, a substantially cylindrical cutter mounted on said core member adjacent one end thereof, a hollow open-ended perforated cylinder mounted for free rotation on said cutter as said shaver is moved through alternate oppositely directed shaving strokes with said cylinder engaging the skin of the user, said core member having an enlargement fixedly secured to said one end thereof formed to provide a thrust bearing for said perforated cylinder, a cylindrical handle mounted on and removably secured to said core member, stop means on said handle and core member for accurately longitudinally positioning said handle on said core member, and means on said handle formed to provide a second thrust bearing for said hollow cylinder, said thrust bearings being spaced to provide for end play of said hollow cylinder during rolling engagement thereof with the skin, and a lost motion connection between said cutter and said core member for limiting to a predetermined angle the relative rotation therebetween whereby said cutter rotates with said hollow cylinder during an initial portion of each shaving stroke following a reversal of the direction of travel and is held against rotation relative to said core member and said handle during the remaining portions of each stroke.

5. A shaver comprising a core member, a cutter rotatably mounted on said core member adjacent one end thereof, a hollow perforated cylinder mounted for free rotation on said cutter, said core member having an enlargement fixedly secured to said one end thereof formed to provide a thrust bearing for said perforated cylinder, a cylindrical handle mounted on and removably secured to said core member, means on said handle formed to provide a second thrust bearing for said hollow cylinder, and a lost motion connection between said cutter and said core member for limiting to a predetermined angle the

relative rotation therebetween whereby said cutter rotates with said hollow cylinder during an initial portion of each shaving stroke following a reversal of the direction of travel and is held against rotation relative to said core member and said handle during the remaining portions of each stroke, as said shaver is moved through alternate oppositely directed shaving strokes with said cylinder engaging the skin of the user.

6. A shaver comprising a core member, a hollow perforated cylinder mounted for free rotation about the axis of said core member for rolling engagement with the skin, a cutter mounted on said core member within said perforated cylinder, a handle, bushing means within said handle for receiving said core member in axially slideable but non-rotatable relation, means on said core member and said handle respectively forming thrust bearings for engaging the opposite ends of said perforated cylinder, and means carried by said handle and engageable with said core member for securing said handle to said core member in axially fixed relation and for releasing said core member from said handle to permit axial disassembly of said cutter, cylinder and handle.

7. A shaver comprising a core member, a hollow perforated cylinder mounted for free rotation about the axis of said core member for rolling engagement with the skin, a cutter mounted on said core member within said perforated cylinder, means fixedly secured to said core member adjacent one end of said cutter forming a thrust bearing for one end of said perforated cylinder, a hollow cylindrical handle, bushing means within said handle for receiving said core member in axially slideable but non-rotatable relation, means on said handle forming a thrust bearing for the opposite end of said perforated cylinder, and means carried by said handle threadedly engaging said core member for effecting axial movement therebetween to assemble said shaver with said perforated cylinder disposed between said thrust bearings and to release said core member from said handle to permit axial disassembly of said cutter, cylinder and handle.

8. A shaver comprising a core member, a hollow perforated cylinder mounted for free rotation about the axis of said core member for rolling engagement with the skin, a cutter mounted on said core member within said perforated cylinder, means fixedly secured to said core member adjacent one end of said cutter forming a thrust bearing for one end of said perforated cylinder, a hollow cylindrical handle, bushing means within said handle for receiving said core member in axially slideable but non-rotatable relation, means on said handle forming a thrust bearing for the opposite end of said perforated cylinder, an end cap secured to the end of said handle opposite from said thrust bearing in axially fixed but rotatable relation, and means carried by said end cap and extending into said handle for threadedly engaging said core member, whereby rotation of said end cap relative to said handle causes relative axial movement of said handle and said core member to effect assembly and disassembly of said shaver.

9. A shaver comprising a cutter assembly including a core member, a cutter mounted on said core member, and a thrust bearing on said core member adjacent one end of said cutter; a hollow perforated cylinder adapted to be telescoped over

said cutter into engagement with said thrust bearing; and a handle assembly including a hollow handle for telescopically receiving said core member, a thrust bearing on said handle for engaging the end of said perforated cylinder opposite from said thrust bearing of said cutter assembly, and a rotatable member carried by said handle for threadedly engaging said core member within said handle for effecting relative axial movement of said handle assembly and said cutter assembly selectively to confine said perforated cylinder between said thrust bearings and to separate said assemblies for removal of said cylinder.
